EDWARD B. HESS AND LEWIS C. MYERS, OF BROOKLYN, NEW YORK, ASSIGNORS, BY MESNE ASSIGNMENTS, TO ROYAL TYPEWRITER COMPANY, INC., OF NEW YORK, N. Y., A CORPORATION OF NEW YORK.

RIBBON-SPOOL FOR TYPE-WRITING MACHINES.

1,156,141.

Specification of Letters Patent.

Patented Oct. 12, 1915.

Application filed November 15, 1913. Serial No. 801,167.

To all whom it may concern:

Be it known that we, EDWARD B. HESS, of the borough of Brooklyn, county of Kings, and State of New York, and LEWIS C. MYERS, of the borough of Brooklyn, county of Kings, and State of New York, citizens of the United States of America, have jointly invented certain new and useful Improvements in Ribbon-Spools for Type-Writing Machines, of which the following is a specification.

This invention relates to movable, interchangeable ribbon spools for type writing machines, particularly adapted to be used on the well known Royal typewriting machine and especially in conjunction with the automatic reversing trip mechanism described and claimed in Letters Patent of Lewis C. Myers, No. 1,084,656, granted January 20, 1914.

The novel features of this ribbon spool will now be fully described, reference being had to the accompanying drawings, in which:

Figure 1 is a plan view of the complete spool; Fig. 2, a plan view showing the top plate and cap removed; Fig. 3, an underneath view of the spool; Fig. 4, shows a side elevation of the spool mounted upon its vertical carrying shaft; Fig. 5, a vertical section of the spool; Fig. 6, illustrates the cap in a partly finished condition; Fig. 7, shows the same finished; Fig. 8, a plan view of a disk with a plurality of openings or notches, carried by the vertical spool shaft with which a pin depending from the bottom flange of the spool is adapted to engage; Fig. 9, illustrates a ribbon leader adapted to be secured to the hub or core of the spool, and Fig. 10, illustrates a modification in the construction of the core.

The spool consists of a top plate 11, a bottom plate 12, a hollow hub or core 13 and a central bearing piece 14. It has also depending from the bottom plate 12 a projection, as a drive pin 15, by which the spool is connected to a vertical drive shaft, and a spring actuated lever adapted to co-act with an operating part of an automatic spool reversing trip, as hereafter described.

The hollow hub or core 13 is provided with projections 16 at each of its ends, three being shown, which enter corresponding openings

in the top and bottom plates arranged so that the hub or core is co-axial with the plates, said projections being riveted over at the outer sides of the plates and affording the only means by which the main parts of the spool are held together. The bearing piece 14 has a central bore and its ends are flattened, as by milling, to snugly seat in correspondingly shaped openings formed centrally in the plates, whereby it is held with the axis of the bore coincident with the axis of the spool but it is in nowise fastened to the plates, being simply held in place between the plates by the rigid connection afforded by the hollow core. This hollow core has a flat surface 17, to which the end of the ribbon may be attached, it generally being preferred to secure one end of a ribbon leader 18 to said flat surface by a large head screw 19, which screws into the central bearing piece 14, as shown in Fig. 2. The head of this screw is rounded, so that when properly seated in place the contour of the cylindrical surface of the hollow core is maintained. To the other end of the ribbon leader 18 is attached a clasp 20 adapted to hold a ribbon.

Another flattened portion or recess 20' is formed on or in the cylindrical wall of the hollow core 13 into which may pass the upper branch 21 of a trip lever when the tape leader or tape is wrapped around the core, the outer surface of this branch being formed to maintain the circular contour of the core. The trip lever is pivoted to ears 22 formed downwardly from the bottom plate 12, and has a lower branch 23 substantially at right angles to the branch 21 and about parallel to the plate 12 when the branch 21 is held within the circle of the core by the ribbon. Now when the branch 21 is released from the pressure of the ribbon the lower branch 23 is thrown downwardly from the plate by a torsional spring 24 and is then in position, as the spool is rotated, to act on a trip device of a spool reversing mechanism.

It is found advantageous to be readily able to lock a removable spool, of the character described, in any circular position on its carrying shaft, here shown as a vertical shaft 25, and not have to select any definite position for such locking action. With this end in view a plurality of openings, suitably

arranged, are provided on the shaft 25 into any one of which the projection or pin 15, depending from the bottom plate may be set, thus insuring rotation of the spool with the shaft. To provide these openings a disk or wheel 26 is secured to the shaft having in its periphery a series of notches 27. The spool rests on the disk and the shaft extends into the bore of the central bearing piece 14 to within a short distance of the upper end of the said bore, leaving room for the neck of a cap. This cap 28 may be of flat disk form with a neck 29, as shown at Fig. 6, and the disk then cupped as shown at Fig. 7, leaving the central neck 29 sufficiently long to hold the cap in place on the top of the spool, with the neck fitting into the upper end of the bore of the central bearing piece 14. This cap imparts a finished appearance to the spool besides covering parts that are objectionable when exposed.

When it is desired to attach a ribbon directly to a spool, then the hollow core 13 may have formed inside prongs 30, Fig. 10, over which the end of the ribbon may be placed, said prongs being formed so as not to destroy the circular continuity of the core.

In the construction herein disclosed the hollow hub 13 positively holds the flanges together. The central bearing piece spaces the flanges fixedly apart and also, while not affixed to them in any way, is interlocked loosely with them so that they and the part 14 are necessarily positively revolved together whenever power to rotate the spool is applied to either. The joint positive rotation of the flanges and hub 13 and the center piece 14 is not therefore dependent upon any riveting or upset binding together or connecting of the parts. The operation of upsetting the ends of the part 14 is eliminated and the completed spool is stronger and better and more certain of perfect operation.

We claim:

1. A ribbon spool having two depending projections on its bottom plate in combination with a vertical spool supporting shaft 50 having a lateral extension with openings for receiving one of said depending projections, the other projection being movable and adapted to contact with the trip device of a reversing mechanism.
- 55 2. A ribbon spool for typewriting machines comprising two plates and a hollow core to which the plates are fastened and a bearing piece disconnectedly held centrally between the plates and interlocked there-

with, the said hollow core affording the only means for holding the parts together.

3. A ribbon spool for typewriting machines comprising two plates each having a series of slots or openings and a hollow core having lugs on its ends adapted to enter the slots of the plates and to which the plates are fastened by riveting and a bearing piece disconnectedly held centrally between the plates and interlocked therewith, the said hollow core affording the only means for holding the parts together.

4. A ribbon spool for typewriting machines comprising two plates and a hollow core to which the plates are fastened, a bearing piece disconnectedly held centrally between the plates, and having a central bore extending through it, the said hollow core affording the only means for holding the parts together and a cap adapted to cover the central part of the top plate and its attached parts and having a stem seated in the central bore of the bearing piece.

5. A ribbon spool for typewriting machines comprising two plates and a hollow core to which the plates are fastened, a bearing piece disconnectedly held centrally between the plates and having a central bore extending through it, the said hollow core affording the only means for holding the parts together, a cap adapted to cover the central part of the top plate and its attached parts and having a stem seated in the central bore of the bearing piece, a projection depending from the bottom plate, and a vertical shaft on which the spool is seated and having a lateral extension provided with a plurality of openings with any of which the depending projection is adapted to engage.

6. A ribbon spool for a typewriting machine having on one of its flanges a depending projection adapted to engage the spool-driving means, and having also on said flange a pivotally mounted spring controlled lever having an arm engaged by the ribbon when the latter is wound on the spool and another arm the outer portion of which has a curved edge adapted to engage the trip device of the ribbon-reversing mechanism when the ribbon is unwound from the spool and said first-mentioned arm has been released.

In testimony whereof, we have hereunto subscribed our names.

EDWARD B. HESS.
LEWIS C. MYERS.
